CLOTHESLINE REEL

Carl S. Shilling, Chicago, Ill.

Application May 18, 1948, Serial No. 27,757

2 Claims. (Cl. 242—100)

1

This invention relates to a clothes line reel and particularly to a reel that may be demounted from the conventional clothes line posts and stored in the basement of a home or the like in order that the clothes line may be protected from dirt and soot.

Many clothes line reels have been made and sold, but most of them have been unsatisfactory for one or a combination of the following reasons:

(a) Reels holding clothes lines that are not demountable become dirty and unusable.

(b) Reels that do not easily and conveniently play out the clothes line and permit the housewife to tighten and fix the line in usable positions on the clothes line posts are not satisfactory.

(c) Reels that tangle and knot the lines soon become unusable and too troublesome to be conveniently operated and are soon discarded.

(d) Reels that do not accommodate themselves to a wide variety of clothes line posts are soon discarded.

It is the particular object of the present invention to provide a clothes line reel that will obviate the difficulties of the reels of the prior art and to provide a practical and economical reel that can be purchased and conveniently used by the modern housewife.

Other objects and benefits will be disclosed by the following descriptions and drawings in which:

Fig. 1 is a sidewise elevation view of my improved demountable clothes line reel mounted by a mounting bracket on an ordinary clothes line post;

Fig. 2 is an endwise view of the reel shown in Fig. 1;

Fig. 3 is a top plan view of my reel with the clothes line thereon applied to conventional clothes line posts;

Fig. 3A is an elevation view of the reel post thereof;

Figs. 4 and 5 are sidewise and plan views of the straight type of pulley bracket which will later be explained; and

Figs. 6 and 7 are plan and elevation views of an angle clothes line pulley bracket shown applied to the clothes line posts in Fig. 3.

Now referring to the drawings, and at the outset to Figs. 1 and 2, I show dual strap brackets 10 and 12 attached in a joined base shank 13 by rivets as clearly shown in the drawings. Through the side of the frame member 10, I show a T-slot 11 which is designed to support the reel and its line on a nail or screw which will be attached to a wall or the like in the basement or other convenient spot in the house. One of the

main ideas of this invention is to provide a clothes line reel that can be easily detached from the clothes line posts and stored with its line in the house in order to avoid dirt and soot which accumulates on clothes lines if they are left outdoors.

At the top of the frames 10 and 12 I mount a handle 14 by a rivet or the like in order to provide ready means to support and transport the reel when it is desirable. Between the frames 10 and 12 I mount a conventional reel 16 having side flanges 16a and 16b which are mounted on a central axle 17 which extends through the outside frame 12 in a squared end 17s to attach a conventional handle 18 which is secured to the squared end 17s by a screw 17b as shown. On the inside of the reel flange 16b I show ratchet corrugations 16r as clearly shown in Fig. 2. I propose to form the reel 16 in a single casting from which I punch out the ratchet openings 16r in the flange 16b.

On the side of the frame 11 I hinge a ratchet dog 18 on a rivet 19 to coact with the ratchet openings 16r as shown. Also, it will be noted that in the side of the frame 10 I lance a projection 20 which will provide means to disengage the ratchet dog 18 by holding it in upright position as shown in dotted outline in Fig. 2. A conventional clothes line 21 is fastened on the reel in the usual way and on the outside end of the line 21 I mount a swivel connection 22 which connects a conventional spring hook 23 as shown in Fig. 1 and which is used to attach the line to a conventional hook eye as shown in Fig. 3.

The shank end of the frame 13 is attached to a shank support member 24 having holes 24f to accommodate screws in order that it may be attached in a convenient location on a conventional clothes line post. The support member 24 has a slot 24s into which the shank 13 is inserted as clearly shown in Figs. 1 and 2. The support member 24 also has a hinged dog 25 hinged on ears 24b and it will be noted that the upper outside end of the dog 25 projects outwardly in a weighted fashion in order to urge the dog 25 inwardly by gravity into a slot 26 perforated through the shank 13. By this construction, it will be obvious that my reel can be inserted in the support member and securely fastened therein by means of the dog 25 in the slot 26. In the same manner, it will be appreciated that the reel may be easily removed from the support member 24 by releasing the dog 25 from the slot 26 whereupon the entire reel may be removed for storage

and protection of the clothes line as heretofore described.

By referring to Fig. 3, it will be observed that my reel can be mounted on a post and the clothes line carried in pulley brackets of a conventional design and which are completely illustrated in Figs. 4, 5, 6 and 7. Careful observation of Fig. 3 will disclose that my reel may be conveniently mounted on a post, then the clothes line released upwardly through threading contact with the handle 14 as clearly shown in Fig. 3A into a straight bracket as shown in Figs. 4 and 5, thence to various angle brackets attached to the posts. By this arrangement the clothes line may be laid in almost any arrangement of clothes post that would be found in the ordinary residence yard. The pulley brackets as illustrated in Figs. 4, 5, 6 and 7 are a part of my reel equipment and they provide means, as clearly illustrated in Fig. 3, whereby the clothes line may accommodate almost any position of the clothes posts.

Again referring to the reel shown in Figs. 1 and 2, it will be appreciated that after the reel is mounted in the bracket 24 and fixed by the dog 25 in position on the post, the clothes line can be reeled out by placing the ratchet dog 18 in the dotted line position as shown in Fig. 2 and supported in that position by the projection 28 on the side frame 10. When the line is threaded on the pulley brackets as shown in Figs. 4, 5, 6 and 7, the ratchet dog 18 may be placed in operating position with respect to the ratchet opening 16₇ in the side flange 16₆ and thereupon the line can be securely tightened in position to support the clothes. When the clothes are removed from the line, the spring hook 23 can be removed from the hook eye and the line placed securely and compactly on the reel, whereupon it can be removed and stored in the basement of the home, thus avoiding dirt and soot if the line was exposed outdoors.

From the above description, it will be obvious that I have avoided many of the difficulties of the clothes line reels of the past and have provided a convenient and economical demountable clothes line reel that will serve its purpose in the modern household.

Having thus described my invention, I now claim as new:

1. In a clothes line reel, a frame comprising a pair of metal straps having their upper ends spaced apart, a handle member connecting said spaced apart ends, one of said straps having an angular portion at its lower end secured to the other strap in overlapping relation to form a shank at one side of the frame, said shank having a slot, a support for said reel having a socket for receiving said shank and a locking dog pivoted to said support and adapted for entering said slot for anchoring said frame to said support.
2. In a clothes line reel, a rectangular line reel carrying frame having a shank portion adjacent its lower end, said shank being of polygonal cross section and having a slot extending therethrough, a support for said frame having a socket with a polygonal opening adapted for receiving said shank therethrough, and a counterweighted locking dog pivoted upon said support and having one end arranged for engaging through said slot in said polygonal shank for anchoring said shank vertically in said support, said polygonal means and said dog both counteracting rotary motion of said reel carrying frame relatively to said support socket.

CARL S. SHILLING.
